ENGINE STARTER DRIVE

William L. McGrath, Elmira, N. Y., assignor to
 Eclipse Machine Company, Elmira Heights,
 N. Y., a corporation of New York

Application June 13, 1934, Serial No. 730,517

24 Claims. (Cl. 74—7)

This invention relates to an engine starter drive and more particularly to that type of starting gearing which automatically connects a starting motor to an engine to be started, and disconnects the same when the engine becomes self-operative. This application is a continuation in part of the prior application of William L. McGrath, Serial Number 689,279, filed September 13, 1933.

- 10 It is an object of the present invention to provide a novel starter drive which is reliable and efficient in operation and particularly adapted to insure smooth and continuous cranking under adverse conditions.
- 15 It is a further object to provide a construction in which the torque is transmitted in part through a yielding driving connection and in part through supplemental frictional clutching connections that are automatically closed before cranking torque is applied to the yielding driving connection.

It is a further object to provide a construction in which the torque is transmitted in part through one or more frictional clutches that are automatically closed before the cranking torque is applied to the drive spring, thus largely increasing the life of the spring and of the drive.

- 20 It is another object of the invention to provide such a device which is designed to resist pumping of the driving pinion during cranking, toward and away from its fully engaged position as the engine passes over its compression points.

It is a further object to provide such a device embodying a torsion spring with radially flattened convolutions, and provisions for causing the convolutions of the spring to be supported laterally while it is torqued.

Further objects and advantages will be apparent from the following description taken in connection with the accompanying drawing in which:

Fig. 1 is a side elevation partly in section of one embodiment of the invention showing the parts in normal or idle position;

Fig. 2 is a similar view of a second embodiment of the invention showing the parts in driving position;

Fig. 3 is a view similar to Fig. 2 showing the parts in the position assumed in case a tooth of the pinion abuts a tooth of the engine gear; and

Fig. 4 is a similar view with the mounting sleeve eliminated and the screw shaft, driving head and stop for the control member mounted directly on the armature shaft.

Referring first to Fig. 1 of the drawing, there

is shown a power shaft 1 which is preferably the extended armature shaft of a starting motor, not shown. An engine driving member in the form of a pinion 2 is slidably journaled on the shaft 1 and is arranged to be moved longitudinally into and out of engagement with a toothed member such as a flywheel gear 3 of the engine to be started, and to be rotated from the power shaft in order to crank the engine.

Means for moving the pinion 2 into and out of mesh with the engine gear and for rotating the same is provided comprising a hollow screw shaft 4 and a transmission member in the form of a nut 5 threaded thereon and rigidly connected to the pinion 2 by means of a barrel 6 which is 15 suitably fixed at its ends to the nut and pinion. Screw shaft 4 is freely journaled on a mounting and actuating member in the form of a hollow sleeve 15 on the power shaft. Shaft 4 is yieldably driven from the power shaft 1 by means of a torsion spring 7 having radially flattened convolutions and suitably anchored to the screw shaft at one end as by means of a stud 8, and to the power shaft 1 at its other end as by means of a bolt 9 traversing a driving head 11 formed on or 25 fixed to the sleeve 15 and keyed to the power shaft 1. It will be understood that the radial flattening of the convolutions of the spring renders the spring comparatively limber with respect to axial compression, with increased torque capacity, as is well known in this art. Space 12 is provided between the end of the screw shaft 4 when in normal position and the abutment formed by the adjacent end of the driving head 11 in order to permit longitudinal movement of 35 the screw shaft toward the driving head against the compression of the spring 7.

An abutment is provided in the form of a stop ring 13 for limiting the longitudinal motion of the nut 5 in a direction to mesh the pinion 2 and 40 for defining the normal position of the screw shaft 4 on sleeve 15. The stop ring 13 is provided with an extended flange 14 telescoped over the end of the screw shaft 4 in position to be engaged by the nut 5 when in driving position, 45 and is longitudinally fixed with respect to the power shaft 1, by means of an abutment 16 on the sleeve 15 as shown in Fig. 1, or by means of a threaded connection with said sleeve as shown in Figs. 2 and 3.

In order to prevent rebounding of the pinion and nut when they are thrown back to idle position after the engine starts, the screw shaft 4 is provided with a smooth portion 17 adjacent the idle position of the nut which permits the nut to 55

run off the threads and rotate freely. Means for insuring reengagement of the nut with the threads of the screw shaft are provided in the form of a compression spring 18 located between

5 the stop ring 13 and the pinion end of the barrel 6, which spring is under slight compression when the nut runs off the threads of the screw shaft.

10 Means for normally maintaining the nut in idle position is provided in the form of a light compression spring 19 located between the nut and the stop ring 13.

15 In the operation of this embodiment of the invention, rotation of the power shaft 1 is transmitted through the torsion spring 7 to the screw shaft 4. The pinion and barrel assembly by reason of its inertia to rotation, is moved longitudinally by the nut 5 until the pinion 2 is fully meshed with the engine gear 3 at which time the nut 5 engages the stop ring 13. The screw shaft 20 4 thereupon moves backward, compressing the spring 7 until the space 12 is taken up, after which the pinion, nut and screw shaft are driven from the power shaft 1 through the supplementary frictional clutching connections established between the abutments on the sleeve 15 25 and the screw shaft 4 and nut 5 and through the spring 7, as indicated in Fig. 2. A ring 21 of fiber or other suitable material is preferably provided between the abutting surfaces of the 30 screw shaft and driving head which aids in controlling the supplemental frictional transmission and also prevents seizing of said surfaces.

35 When the engine becomes self-operative, the acceleration of the pinion 2 by the engine gear causes the nut 5 to overrun the screw shaft, whereby the screw shaft is permitted to return to its normal position under the expansive action of the spring 7 and thereafter the nut 5 is thrown back to its idle position where it is permitted to 40 overrun as above described until its rotational momentum has become dissipated. The spring 18 then serves to place the nut in initial engagement with the screw threads in position for re-actuation as above set forth.

45 It will be noted that since the screw shaft 4 has been displaced longitudinally and bears against the driving head 11 during the cranking operation, any pumping action of the pinion as the engine passes over its compression points is 50 resisted by the friction between the abutting surfaces of the nut, stop ring 13, and screw shaft. Moreover, in case the tendency of the pinion to pump is not entirely overcome by such friction, the screw shaft 4 may shuttle back and forth 55 along its longitudinal path of travel while the pinion 2 is still held in its fully meshed position by the expansive force of spring 7, such longitudinal movement of the screw shaft being effectively damped by the friction between the 60 threads of the screw shaft and the nut 5.

65 It is further to be noted that the compression of spring 7 prior to the application of the cranking load causes the convolutions of the spring to be brought into supporting relation with each other, so that the tendency of the flattened convolutions to tip over when the spring is torqued, is overcome. Moreover, the friction produced between the convolutions of the spring when it is compressed and torqued assists in damping the 70 torsional vibrations of the spring. It will be understood that whether or not the spring 7 is compressed solid as indicated in Fig. 2 when the screw shaft is forced against the driving abutment 11 by the screw jack action of the nut 5, the frictional engagement between the convolu-

tions of the spring will be produced when the spring is torqued. These features have been found to increase the durability and efficiency of the spring.

5 In the embodiment of the invention illustrated in Figs. 2 and 3, the sleeve 15' is formed integral with the driving head 11, and the stop member 13' is formed as a nut threaded on the end of the sleeve 15' and rigidly fixed thereon in any suitable way as indicated at 22. A ring 10 of 10 bronze or other suitable material and corresponding to the ring 21 is preferably interposed as indicated between the nut 5 and stop member 13'. The remaining parts are the same as illustrated in Fig. 1 and are similarly numbered, 15 and the operation of the drive is the same as above set forth.

20 In case in the operation of the drive a tooth of the pinion comes into engagement with a tooth of the flywheel gear as illustrated in Fig. 3, the 20 obstruction of the motion of the pinion 2 causes the screw shaft 4 to move back, compressing the spring 7 and thereby causing the nut 5 to bind on the screw shaft and transmit torque to the pinion. The pinion is thus indexed and is thereupon snapped into mesh by the expansion of the spring 7. Cranking then takes place as usual.

25 The construction shown in Fig. 4 functions in a similar manner. The constructional differences are that the sleeve 15 is entirely omitted and 30 the screw shaft 4, the drive head 11' and the stop or abutment 13'' are directly mounted on the armature shaft, the stop or abutment 13'' being fixed thereto by a suitable rigid connection. While this embodiment lacks the unitary characteristic that the sleeve 15 imparts to the device, the functioning thereof, after once installed, is similar.

35 It is particularly pointed out that by the present invention, without sacrificing the many advantages of a yielding driving connection in the form of a torsion spring between the armature shaft and the hollow screw shaft through which heretofore all of the electrical torque and the kinetic energy of rotation of the armature and associated 45 parts passed, a supplemental frictional transmission is automatically established between the armature shaft and the hollow screw shaft and between the armature shaft and the pinion assemblage. This results from the novel mode of operation of the hollow screw shaft in this combination in that it is automatically moved longitudinally in one direction in the normal operation of the drive to subserve the functions of establishing the supplemental frictional transmissions, as well as 50 to compress the coils of the drive spring into supporting relationship. This mode of functioning has not only improved the operation of the drive in the respects noted but has increased the life of the drive spring and the drive itself to a marked 55 extent. Further, the ability of the hollow screw shaft to move longitudinally in the opposite direction when the engine goes over compression and tends to demesh the pinion from the flywheel gear, insures that the pinion remains in fully meshed 60 position.

65 The inventive idea is susceptible of various embodiments of which the foregoing are examples. The invention is not, however, limited thereto, the bounds thereof being set in the appended 70 claims. It is expressly understood with respect to said claims that, except in those in which the hollow shaft 15 is expressly stated as an element, the matter of the direct or indirect mounting of the hollow screw shaft 4, the abutment 13, 13', 13'' 75

and the drive head 11 on the armature shaft 1 is immaterial; and that the language of such claims is meant to cover both constructions.

It is further pointed out that while the inventive idea subserves its maximum benefits and advantages when embodied in a drive employing a torsion spring between the drive head and the screw shaft for reasons heretofore stated, so far as the new result of the automatic establishment of supplementary clutching connections to transmit part of the torque by the longitudinal movement of the screw shaft in the normal operation of the drive, this may be effected by a yieldable driving connection between the drive head and the screw shaft other than a torsion drive spring; and certain of the claims herein presented are not limited to such a torsion or other spring but are directed broadly to the automatic establishment of the supplementary clutching connections by the longitudinal movement of the screw shaft in combination with a yielding driving connection in the direct line of torque transmission.

What is claimed is:

1. In an engine starter, a unitary drive including a mounting and actuating member, a screw shaft loosely mounted thereon, a torsion spring connecting said mounting member and shaft, a nut threaded on the screw shaft, an engine driving member connected for rotation and longitudinal movement with the nut, and means on the mounting member arranged to be engaged by said nut for limiting longitudinal movement of the nut in the direction to engage the engine driving member and for transmitting driving torque from the mounting member to the nut.

2. In an engine starter, a unitary drive including a mounting and actuating member, a screw shaft loosely mounted thereon, a torsion spring connecting said mounting member and shaft, a nut threaded on the screw shaft, an engine driving member connected for rotation and longitudinal movement with the nut, means on the mounting member arranged to be engaged by said nut for limiting longitudinal movement of the nut in a direction to engage the engine driving member, and means on the mounting member for limiting longitudinal movement of the screw shaft in the direction to compress the spring and for transmitting driving torque from the mounting member to the screw shaft in the normal operation of the drive.

3. In an engine starter drive, a power shaft, a screw shaft loosely mounted thereon, a torsion spring having normally spaced convolutions anchored at one end to the power shaft and the other to the screw shaft, a nut threaded on the screw shaft, an engine driving member loosely mounted on the power shaft, and connected for rotation and longitudinal movement with the nut, an abutment on the power shaft limiting longitudinal movement of the nut in the direction to mesh the pinion, an abutment on the power shaft for limiting longitudinal movement of the screw shaft in the direction to compress the spring and for establishing torque transmitting clutching relationship between the screw shaft and its abutment in the normal operation of the drive.

4. In an engine starter, a unitary drive including a mounting and actuating member, a screw shaft loosely mounted thereon, a torsion spring having normally spaced convolutions anchored at one end to the mounting member and at the other to the screw shaft, a nut threaded on the screw shaft, an engine driving member connected for rotation and longitudinal movement with the nut,

an abutment on the mounting member arranged to be engaged by said nut for limiting longitudinal movement of the nut in the direction to engage the engine driving member, an abutment on the mounting member for limiting longitudinal movement of the screw shaft in the direction to compress the spring and for establishing torque transmitting clutching relationship between the screw shaft and its abutment.

5. In an engine starter drive, a power shaft, an engine driving member loosely mounted thereon for movement into and out of engagement with a member of the engine to be started, means including a coiled spring having normally spaced flattened convolutions for actuating the engine driving member from the power shaft, means for compressing said spring to cause the adjacent convolutions to support each other prior to the application of the cranking torque thereto, and means for limiting said compression and frictionally supplementing the transmission of torque by the spring.

6. In an engine starter drive, a power shaft, an engine driving member loosely mounted thereon for longitudinal movement into and out of engagement with a member of an engine to be started, a hollow sleeve fixed to the power shaft, a hollow screw shaft loosely mounted on the sleeve and yieldably connected for rotation and longitudinal movement therewith, a nut threaded on the screw shaft and connected to actuate the engine driving member and a stop on said sleeve independent of said screw shaft adapted to be engaged by said nut when in driving position.

7. In an engine starter drive, a power shaft, an engine driving member loosely mounted thereon for longitudinal movement into and out of engagement with a member of an engine to be started, a hollow sleeve fixed to the power shaft, a hollow screw screw shaft loosely mounted on the sleeve and yieldably connected for rotation and longitudinal movement therewith, a nut threaded on the screw shaft and connected to actuate the engine driving member, a stop on said sleeve adapted to be engaged by said nut when in driving position, and a stop on said sleeve adapted to limit longitudinal motion of the screw shaft due to the driving reaction of the nut.

8. In an engine starter drive, a power shaft, an engine driving member loosely mounted thereon for longitudinal movement into and out of engagement with a member of the engine to be started, a hollow sleeve fixed to the power shaft, a hollow screw shaft loosely mounted on the sleeve, a coiled spring having spaced convolutions anchored at its ends to said sleeve and screw shaft respectively, a nut threaded on the screw shaft and connected to actuate the engine driving member, a stop on said sleeve adapted to be engaged by said nut when in driving position, and a stop on said sleeve adapted to limit compression of said spring.

9. In an engine starter drive, a power shaft, an engine driving member loosely mounted thereon for longitudinal movement into and out of engagement with a member of the engine to be started, a hollow screw shaft loosely mounted on the power shaft and yieldably connected thereto for rotation therewith and longitudinal movement with respect thereto, a nut threaded on the screw shaft and connected to actuate the pinion, a stop fixed rigidly to the power shaft independent of said screw shaft to be engaged by the nut when in driving position, a yielding connection between the nut and stop urging the nut toward

- idle position, said screw shaft having a smooth portion which permits the nut to run off the threads in its idle position, and yielding means between the stop and the engine driving member for insuring reengagement of the nut with the threads.
10. In an engine starter drive, a power shaft, a screw shaft loosely mounted thereon, a driving head and an engine driving member also mounted thereon, a yielding driving connection between said drive head and screw shaft, a control member threaded on said screw shaft and connected to said driving member to rotate and move the same longitudinally, and abutment means mounted on the power shaft limiting the movement of said control member and cooperating therewith to cause relative rotation of the screw shaft and control member to move said screw shaft longitudinally and establish a torque transmitting clutching relationship between the screw shaft and the drive head in the normal operation of the drive.
11. In an engine starter drive, a power shaft, a screw shaft loosely mounted thereon, a driving head and an engine driving member also mounted thereon, a yielding driving connection between said drive head and screw shaft, a control member threaded on said screw shaft and connected to said driving member to rotate and move the same longitudinally, and means including abutment means mounted on the power shaft limiting the movement of said control member and cooperating therewith to establish a torque transmitting clutching relationship between said control member and said abutment means in the normal operation of the drive.
12. In an engine starter drive, a power shaft, a screw shaft loosely mounted thereon, a driving head and an engine driving member also mounted thereon, a yielding driving connection between said drive head and screw shaft, a control member threaded on said screw shaft and connected to said driving member to rotate and move the same longitudinally, and means including abutment means mounted on the power shaft limiting the movement of said control member and cooperating therewith to cause relative rotation of the screw shaft and control member to move said screw shaft longitudinally and establish a torque transmitting clutching relationship between the screw shaft and the drive head and between said control means and abutment means in the normal operation of the drive.
13. In an engine starter drive, a power shaft, a screw shaft loosely mounted thereon, a driving head and an engine driving member also mounted thereon, a yielding driving connection between said drive head and screw shaft in the line of torque transmission, a control member threaded on said screw shaft and connected to said driving member to rotate and move the same longitudinally, and abutment means mounted on the power shaft limiting the movement of said control member and cooperating therewith to cause relative rotation of the screw shaft and control member to move said screw shaft longitudinally and establish a torque transmitting clutching relationship between the screw shaft and the drive head in the normal operation of the drive.
14. In an engine starter drive, a power shaft, a screw shaft loosely mounted thereon, a driving head and an engine driving member also mounted thereon, a yielding driving connection between said drive head and screw shaft in the line of torque transmission, a control member threaded on said screw shaft and connected to said driving member to rotate and move the same longitudinally, and abutment means mounted on the power shaft limiting the movement of said control member and cooperating therewith to cause relative rotation of the screw shaft and control member to move said screw shaft longitudinally and establish a torque transmitting clutching relationship between the screw shaft and the drive head in the normal operation of the drive.
15. In an engine starter drive, a power shaft, a screw shaft loosely mounted thereon, yielding driving means connecting said shafts, an engine driving member loosely mounted on said power shaft, a control member screw threaded on said screw shaft and connected to said driving member for rotation and longitudinal movement therewith, means on the power shaft limiting longitudinal movement of said control member in one direction and means on the power shaft limiting longitudinal movement of the screw shaft in the opposite direction and establishing torque-transmitting clutching relationship between said control member and its associated means and between the screw shaft and its associated means in the normal operation of the drive.
16. In an engine starter drive, a power shaft, a screw shaft loosely mounted thereon for rotary and longitudinal movement with respect thereto, a yielding driving connection interposed between said shafts, engine driving means having threaded engagement with said screw shaft and capable of longitudinal movement and rotary movement relative thereto to engage and crank the engine, stop means rigid with said power shaft for limiting the movement of said driving means in engine engaging direction, and stop means rigid with said power shaft for limiting the movement of said screw shaft in the opposite direction, said stop means and driving means and said stop means and screw shaft being adapted for torque-transmitting engagement, and said threaded connection causing said driving means and screw shaft to move in opposite directions into such engagement with their respective stop means prior to the application of cranking torque to said yielding driving connection.
17. In an engine starter drive, a power shaft, a screw shaft loosely mounted thereon for rotary and longitudinal movement with respect thereto, a torsion drive spring connecting said shafts, engine driving means having threaded engagement with said screw shaft and capable of longitudinal movement and rotary movement relative thereto to engage and crank the engine, stop means rigid with said power shaft for limiting the movement of said driving means in engine engaging direction, and stop means rigid with said power shaft for limiting the movement of said screw shaft in the opposite direction, said stop means and driving means and said stop means and screw shaft being adapted for torque-transmitting engagement, and said threaded connection causing said driving means and screw shaft to move in opposite directions into such engagement with their respective stop means prior to the application of cranking torque to said drive spring.
18. In a starter drive a power shaft, an engine driving member mounted for movement into and out of engagement with a member of the engine to be started, a torque-transmitting connection between the power shaft and the engine driving member including a spring driving connection

and a friction clutch arranged in parallel, and torque-responsive means for closing said clutch to rotate said engine driving member.

19. In a starter drive a power shaft, an engine driving member mounted for movement into and out of engagement with a member of the engine to be started, a torque-transmitting connection between the power shaft and the engine driving member including a yieldable driving connection and a friction clutch arranged in parallel, said clutch being normally disengaged, and means responsive to the total transmitted torque for closing said clutch to supplement the transmission of torque through the yieldable driving connection.
- 10 20. In a starter drive a power shaft, an engine driving member, a torque-transmitting connection between the power shaft and engine driving member including two yieldable driving connections in parallel, one being constantly effective to transmit torque, and the other being normally loose, and torque-responsive means for tightening the loose connection to cause it to gradually assume the load.
- 15 21. In a starter drive a power shaft, an engine driving member, friction clutch elements connected respectively to the power shaft and driving member, load-responsive means for closing said clutch, and resilient torque transmitting means located adjacent the friction clutch elements for controlling the engagement of said clutch elements.
- 20 25 30

22. In a starter drive a power shaft, an engine driving member, friction clutch elements connected respectively to the power shaft and driving member, load responsive means for closing said clutch and resilient means in the line of transmission of torque from the power shaft to the driving member located adjacent the friction clutch elements for controlling the engagement of said clutch elements.

23. In a starter drive a power shaft, an engine 10 driving member mounted for movement into and out of engagement with a member of the engine to be started, clutch elements connected respectively to the power shaft and driving member, load-responsive means for closing said clutch and 15 yieldable means normally maintaining said clutch elements disengaged and connected between the power shaft and load responsive means to actuate said load-responsive means to cause closure of the clutch.

24. A starter drive including a power member, an engine driving member, torque transmitting connections therebetween including normally loose clutch elements and a coiled spring, said clutch elements being arranged to supplement the 25 transmission of torque through said spring, and means responsive to the torque transmitted by said spring for closing said clutch to relieve said spring from excessive loads.
